ABSTRACT OF THE DISCLOSURE

Oxalic acid is made by oxidizing propylene with at least 50% nitric acid at 40 to 80° C.

The present invention relates to the preparation of oxalic acid by oxidation of propylene.

This application is a continuation of Ser. No. 539,775, now abandoned.

The process most commonly employed in industry for the preparation of oxalic acid is the alkali metal formate process, which consists in decomposing alkali metal formates, such as sodium formate, to alkali metal oxalates by heating, converting the alkali metal oxalates into insoluble calcium oxalate and then liberating the oxalic acid with sulphuric acid. Despite the good yields of oxalic acid which it gives, this process has certain disadvantages from the industrial viewpoint: it is carried out in a number of phases, and there is a high consumption of sulphuric acid converted into calcium sulphate, which is a by-product that is difficult to recover.

It has also been proposed to prepare oxalic acid by oxidation of unsaturated hydrocarbons such as propylene. Thus, in German Pat. 742,053, a process is described for the oxidation of propylene with nitric acid at a temperature between 50° and 70° C., in the presence or absence of oxygen, under normal or higher pressure.

The best yields (80% based on the propylene used up, and 76% based on the propylene employed) have been obtained by using as oxidising agent a mixture of sulphuric and nitric acids in the presence of oxygen, at normal pressure. The presence of sulphuric acid involves technological problems (e.g. recovery and concentration of the oxidation mother liquors, and considerable corrosion of the apparatus). In the absence of sulphuric acid, the yields based on the propylene employed do not exceed 51.5% using oxygen at normal pressure, or 64% under pressure, and do not exceed 44% in the absence of oxygen. It is also known (see U.S. Pat. No. 3,081,345) that the oxidation of propylene by this process is not rapid, and that that portion of the propylene which is not combined in the reaction medium forms with the nitrous vapours (more particularly NO₂) a gas mixture which gives rise to a danger of explosion.

In order to obviate the disadvantages of this process, it has been proposed (in the aforesaid U.S. Pat. No. 3,081,345) to carry out the oxidation of the propylene in two stages: (1) oxidation of the propylene in liquid NO₂ between -30° and +21° C., leading to intermediate products; followed by (2) oxidation between 60° and 120° C. of the products of the first stage by an oxidation medium which is preferably a mixture of sulphuric and nitric acids, but which may also be HNO₃ or NO₂ (with the use of pressure).

This latter process has the disadvantage that it takes place in two stages involving fairly different operating conditions, and above all that it is dependent upon the

use of sulphuric acid for obtaining good oxalic acid yields.

It has not been found that it is possible to obtain oxalic acid in good yields in the absence of sulphuric acid and oxygen, by the oxidation of propylene with nitric acid, by passing gaseous propylene into a liquid medium containing at least 50% by weight of nitric acid and at a temperature of 40 to 80° C.

In the previously described processes, the nitric acid concentration decreases in the course of the reaction, on the one hand because of the increase in the weight of the reaction mass and on the other hand because of the consumption of nitric acid and its entrainment in the nitrous vapours. Moreover, it is found that, as the nitric acid concentration decreases, the quantity of propylene entering into the reaction also decreases, which results in a considerable lowering of the yield and in the formation of a gaseous mixture of propylene and nitrous vapours.

On the other hand, maintaining the nitric acid concentration at 50% or above makes possible a total conversion of the propylene and the production of excellent yields of oxalic acid, in the absence of sulphuric acid. Moreover, it has been found that, in the process of the invention, the quantity of acid which disappears in the form of irrecoverable nitrogen is low. It is known that, when organic compounds are oxidised with nitric acid, the latter is reduced in some cases as far as the irrecoverable nitrogen and nitrous oxide (N₂O); in addition to the recoverable nitrous vapours formed of NO and NO₂, variably combined in the form of N₂O₃, which may be oxidized to regenerate nitric acid. The term "consumption of nitric acid" means the quantity of nitric acid converted into irrecoverable nitrogen or N₂O; it is expressed in mol. of HNO₃ per mol. of oxalic acid formed.

Although the new process may be carried out with highly concentrated nitric acid, it is possible to obtain good yields even with nitric acid of concentrations ranging from 60% to 75% by weight, and the use of such concentrations is preferred.

Various methods may be adopted to ensure that the nitric acid concentration is maintained above 50%. For example, the experimentally determined necessary quantity of fresh nitric acid may be introduced throughout the duration of the reaction. In this case, in order not to dilute the reaction medium, an acid of higher concentration than the starting acid is preferably employed. It is also possible to combine the addition of fresh nitric acid with a recycling through the reactor of nitric acid obtained by oxidation and treatment with water of the nitrous vapours produced by the reaction.

The temperature of the reaction depends upon the nitric acid concentration in the reactor. Generally speaking, the operation may be carried out at temperatures ranging from 40° to 80° C., and preferably from 50° to 70° C.

In practice, the process of the invention may be carried out as follows:

The reactor is charged with a predetermined amount of nitric acid, and propylene is gradually introduced in highly divided form (i.e. as a very fine stream of bubbles) and at a rate which, for a predetermined constant concentration of nitric acid in the reactor, depends upon the speed of the reaction (and therefore upon the temperature). The maximum rate of supply is that at which propylene begins to be detectable in the effluent gases.

Simultaneously, fresh nitric acid, and where appropriate regenerated nitric acid, are added to maintain the nitric acid concentration of the medium at a fixed value of 50% or above.

When the addition of the propylene is complete, the reaction medium is subjected to a finishing to complete the oxidation of the propylene taken up by the reaction medium. During this phase of the process, it is unnecessary to maintain a constant nitric acid concentration in the medium. Generally speaking, the temperature of the finishing phase may be the same as that adopted for the addition of the propylene. The duration of the finishing phase depends upon the temperature. This finishing makes possible a considerable improvement in the oxalic acid yield without increasing the consumption of nitric acid as irrecoverable nitrogen in relation to the amount of propylene introduced. At the end of the finishing phase, the reaction mass is cooled and dihydrated oxalic acid precipitates as white crystals.

Depending upon the operating conditions, up to 90% of the acid in the reaction medium may be isolated by simple filtration. The isolated oxalic acid is washed with water and dried by heating to constant weight. It is found, and this is another advantage of the new process, that the oxalic acid obtained in this way has a purity of 100%.

The reactants and the operating conditions employed in the process according to the invention lend themselves particularly well to continuous industrial working.

The following examples illustrate the invention.

EXAMPLE 1

The apparatus employed is illustrated in the accompanying drawing. It is composed of the following elements: a cylindrical glass reactor 1 having a height of 520 mm., a diameter of 40 mm. and a useful volume of 700 cc.; a conical chamber 2 connected to the lower part of the reactor and connected thereto by a plate 3 of fritted glass No. 3 (porosity 15-40 μ); a pipe 4 for the supply of propylene extending from the apex of the conical chamber, rising laterally along the outer wall of the reactor and connected to a propylene cylinder; a reactor head consisting of a ground glass stopper 5 provided with a thermometer 6, a pipe 7, for the admission of oxygen or inert gas, which terminates above the level of the reaction mass, and a Y-shaped pipe 8 connected on the one hand to a dropping funnel 9 and on the other hand to a column 10 packed with Raschig rings of a diameter of 28 mm. and a height of 80 mm., on which is mounted a coiled condenser 11 (height 150 mm.) supplied with ice-cold water (250 litres per hour) and the atmosphere of which may be placed in communication with an oxygen source 12; a column 13 (height 400 mm., diameter 58 mm.) packed with Raschig rings, below which is mounted a round-bottomed receiver flask 17 which is provided, on the one hand, with a lower lateral pipe connected to the upper part of the condenser 11 and adapted to be connected to the oxygen source 12, and, on the other hand, with an upper lateral pipe; a circulating pump 14 between the receiver flask 17 and the top of the column 13; a column 15 (height 200 mm., diameter 31 mm.), also packed with Raschig rings, on which is mounted a distilled-water reservoir comprising a flow regulating valve in the connecting tube; a spherical receiver flask 18 disposed below the column 15 and connected to the upper lateral pipe extending from the column 13; a bath 19 with thermostat intended for heating the reactor.

Before commencement of an operation, distilled water is introduced into the reservoir 16 and into the flask 17, the bath is adjusted to a temperature of 50° C. and, while a light current of propylene is passed into the reactor to avoid any admission of liquid into the chamber 2, 539.8 g. of 72.2% nitric acid (i.e. 6.20 mol. of HNO₃) are introduced into the reactor through the dropping funnel 9.

When the temperature in the reactor reaches 50° C., the rate of supply of propylene is adjusted to 1.4 litre per hour (0° C./760 mm. Hg).

Oxygen is simultaneously admitted to the outlet of the coiled condenser at a rate of 5.3 litres per hour to ensure

oxidation of the nitrous vapours emanating from the reactor; part of the vapours is condensed by the condenser 11, the coil of which is cooled by a current of ice-cold water, and returns to the reactor; the remainder of the vapours enters the absorption system consisting of the column 13 sprinkled with liquid taken from 17 by the recycling pump 14 and on the other hand through the column 15 which is sprinkled dropwise by water coming from 16.

After reaction at this rate for 30 minutes, 93% nitric acid is gradually introduced into the reactor through the funnel 9. 17.8 g. of propylene (0.424 mol.) are passed through in seven hours, while the total quantity of additional 93% nitric acid amounts to 123.4 g. No trace of propylene is found in the gases leaving the apparatus.

The reaction mass is then cooled to 25° C., and there is passed through the reactor, above the level of the liquid, for about 20 minutes, a current of oxygen at a rate of 10 litres per hour to ensure the degassing of the apparatus and the oxidation of the nitrous vapours. The reaction mixture is then weighed and a test is made to determine the nitric acid concentration of the reaction mass, and another to determine the oxalic acid formed.

The weight of the reaction mass is 616.1 g. The mass is introduced into a three-necked, round-bottomed one-litre flask equipped with a stirring system and a thermometer, and this flask is placed in the preceding apparatus in place of the reactor. The temperature of the products is raised to 50° C. and a current of oxygen is simultaneously admitted (rate of flow 2.3 litres per hour) to the outlet of the coiled condenser. At the end of 4 hours, a test is made to determine the oxalic acid formed, and the finishing is then continued for 19 hours at 50° C.

The contents of the flask are cooled to 25° C. and degassed as before. The weight of the mixture is 578.8 g., i.e. a loss of 84.4 g. during the finishing phase. Two tests are made, one to determine the oxalic acid and the other to determine the nitric acid concentration in the reaction mass.

Determination of the oxalic acid is effected in the conventional manner after it has been isolated by precipitation as calcium oxalate.

The nitric acid balance is established by nitrometric determination by means of the Lunge volumenometer, on the one hand on the reaction mixture after finishing, and on the other hand on the nitric acid liquors resulting from the oxidation of the nitrous vapours in the course of the reaction and in the course of the finishing.

The balance of the reaction is established as follows:

	G.
Weight of anhydrous oxalic acid before finishing	22.5
Weight of anhydrous oxalic acid after finishing for 4 hours	27.6
Weight of anhydrous oxalic acid after finishing for 23 hours	27.6

Oxalic acid yield calculated on the propylene employed: before finishing, 59%; after finishing, 72.2%. Nitric acid concentration in the reactor: before finishing, 64%; after finishing, 61%.

Recoverable nitrogen in the reactor, expressed in mol. of HNO₃: after finishing, 5.62.

Recoverable nitrogen in the total of the acid liquors, expressed in mol. of HNO₃, 1.86.

The consumption of nitric acid in the form of irrecoverable nitrogen expressed in mol. of HNO₃ per mol. of oxalic acid is thus 1.75 mol./mol.

The reaction medium is left for 16 hours at 5-10° C. Dihydrated oxalic acid precipitates as white crystals. The precipitate is filtered off, washed with 100 cc. of ice-cold water on a filter and then dried at 40° C. to constant weight, 25.8 g. of 100% pure product are recovered.

5

EXAMPLE 2

In the apparatus of Example 1, a test was carried out, the conditions and results of which were as set out in the following table:

Nitric acid introduced: 586 g. at 67% (6.24 mol. of HNO_3)

Temperature: 50° C.

100% propylene: rate of flow: 1.5 l./h. on average (at 0° C./760 mm. Hg) duration: 7 hours; weight: 19.2 g. 10 (0.457 mol.)

Oxygen: rate of flow: 5.3 l./h.

Nitric acid added: 150 g. at 93.5%

Weight of the reaction mass before finishing: 687 g.

Finishing: 23 hours at 50° C.

Weight of the reaction mass after finishing: 645 g.

Weight of anhydrous oxalic acid before finishing: 23 g. 15

56% yield calculated on the propylene employed

Weight of anhydrous oxalic acid after finishing for 23 hours: 28.3 g.; 69% yield calculated on the propylene 20 employed

Nitric acid concentration in the reactor, before finishing: 60%

After finishing: 57.5%

Recoverable nitrogen in the reactor expressed in mol. of 25 HNO_3 after finishing: 5.88

Recoverable nitrogen in the acid liquors in mol. of HNO_3 : 2.08

Nitric acid consumption in the form of irrecoverable nitrogen, in mol. of HNO_3 per mol. of oxalic acid: 1.59 30

Weight of dihydrated oxalic acid (100%): 26.3 g.

EXAMPLE 3

In the apparatus described in Example 1, the reactor is replaced by a reactor having the following characteristics:

Height: 450 mm.

Diameter: 30 mm.

Useful volume: 300 cc.

and which has a double jacket for the circulation of water at thermostatically controlled temperature.

In to the reactor are charged 392 g. of 75% nitric acid, the temperature of which is raised to 50° C. by circulation of water through the double jacket. Propylene containing 8% of propane is then passed into the reactor at a

6

rate of flow of 4.94 litres per hour, i.e. 4.54 litres per hour 100% propylene. Gas extractions are effected every 90 minutes at the outlet of the column for the recovery of the nitrous vapours, and chromatographically analysed.

5 Extractions are simultaneously made from the reactor to determine the nitric acid concentration.

The following results were obtained:

Extraction at the time t after the commencement of the reaction	Percent of propylene		
	In the effluent gases	Absorbed in the reactor	HNO_3 , percent in the reaction mass
1 hour 30 minutes -----	0	100	64.9
3 hours -----	Traces	100	51.7
4 hours 30 minutes -----	8.37	84	39.7
6 hours -----	15.5	70	32.3
8 hours -----	35.17	35	28.3

After passage of propylene for 9 hours 30 minutes, the reaction is stopped.

We claim:

1. Process for the preparation of oxalic acid which comprises passing gaseous propylene into aqueous nitric acid at a temperature of 40° to 80° C., the concentration of the nitric acid being maintained throughout the reaction at at least 50% by weight.

2. Process according to claim 1 in which the nitric acid concentration is maintained between 60% and 75% by weight throughout the reaction.

3. Process according to claim 1 in which the reaction temperature is 50° to 70° C.

4. Process according to claim 1, in which the propylene is introduced into the reaction medium as a very fine stream of bubbles at a rate such that no propylene is detectable in the gas leaving the reaction medium.

5. Process according to claim 1 in which after introduction of propylene into the nitric acid has ceased, the temperature of the latter is maintained at 40° to 80° C. to complete the oxidation of the propylene to oxalic acid.
